UNITED STATES PATENT OFFICE.

WILLIAM H. BOUTELL, OF ROCHESTER, NEW YORK, ASSIGNOR TO BOUTELL MANUFACTURING COMPANY, OF ROCHESTER, NEW YORK, A CORPORATION OF NEW YORK.

APPLE-PARING MACHINE.

974,230.

Specification of Letters Patent.

Patented Nov. 1, 1910.

Application filed September 23, 1905. Serial No. 279,752.

To all whom it may concern:

Be it known that I, WILLIAM H. BOUTELL, of Rochester, in the county of Monroe and State of New York, have invented certain new and useful Improvements in Apple-Paring Machines; and I do hereby declare the following to be a full, clear, and exact description of the same, reference being had to the accompanying drawings, forming a part of this specification, and to the reference-numerals marked thereon.

My present invention relates to improvements in machines for paring apples and similar fruit, and particularly of the kind shown in my prior applications, Serial No. 262,682, renewed May 27, 1905, and Serial No. 239,567, renewed Sept 12, 1907, and the purpose of my present invention is to provide certain improvements in the mounting of the paring knife and of the revolute spindles which center and revolve the articles of fruit during the paring operation, and also to provide an improved clutch which is so constructed that it may be operated with the greatest convenience and safety by the attendant, in throwing the machine into and out of operation.

To these and other ends the invention consists in certain improvements and combinations of parts all as will be hereinafter more fully explained, the novel features being pointed out in the claims at the end of the specification.

In the drawing: Figure 1 is a side elevation of a paring machine embodying my improvements. Fig. 2 is a transverse sectional view on the line 2—2 of Fig. 1. Fig. 3 is a plan view of the reel and its connected parts. Fig. 4 is a sectional view on the line 4—4 of Fig. 1. Figs. 5 and 6 are central longitudinal sectional views of an improved clutch, the members being shown respectively as connected and disconnected. Fig. 7 is a detail view of the paring knife and the improved manner of mounting it. Figs. 8 and 9 are detail views of parts of the paring knife mounting, and Fig. 10 is a section through the axis of one of the spindles and its bearing.

50 The same numerals of reference in the several figures indicate similar parts.

My present improvements, as above stated, are particularly applicable to paring machines of the general type shown in my prior applications before-mentioned, com-

prising generally a frame 1 and a reciprocating carriage 2 mounted to operate on suitable ways thereon, the frame being relatively stationary and provided with the fork reel with its revolute fruit receiving forks and suitable operating mechanism for intermittently rotating the reel and operating the forks, and for reciprocating the carriage, while the carriage carries the paring knife and suitable mechanism for operating it.

In the present form of my invention the driving wheel 3 is formed to receive a belt and is loosely mounted on a stud 4, the latter being fixed suitably to the stationary frame. 70 On this stud is also mounted a wheel 5, having the spur gears 6 and 7 thereon and the bevel gear 8, the latter meshing with a wheel 9 which serves to reciprocate the carriage while the gear 6 co-operates with the 75 wheel 10 which serves to rotate the fork reel, the gear 7 co-operating with the pinion 11, the latter being connected through suitable gearing to the pinion 12, which in turn co-operates successively with the pinions 13 80 and 14 of the spindles 15 and 16 of the fork reel 27, these parts being substantially the same as that described in my said application.

The wheels 3 and 5 are provided at their 85 proximate sides with projections 17 and 18 respectively which are arranged to be engaged and disengaged by a relative axial motion of the wheels, and it is preferable to provide these wheels with the extended 90 hubs or sleeves 19 and 20 which extend toward each other and are adapted to support the helical compression spring 21, the latter bearing at its opposite ends against, and normally exerting a pressure tending 95 to separate the wheels, and thereby disengage the co-operating projections thereon. The outer end of the stud is provided with a diametric slot 22 in which is a pivoted cam 23 having a portion 23^a close to the pivot, and a similar portion 23^b on the opposite side of the pivot and at a greater distance therefrom, a projecting portion 23^c intervening the portions 23^a and 23^b, the cam being provided with a handle 24 by means of 100 which it may be conveniently operated into either of the positions shown in Figs. 5 and 6. Resting in the slot 22 of the stud between the cam and wheel 3 is a slidable sleeve 25 having a cylindrical portion sur- 110

rounding the stud and engaging the outer side of the wheel 3, and also having a diametrically formed shoulder 26 extending through the corresponding slot in the stud 5 and adapted to coöperate alternately with the portions 23^a and 23^b of the cam. By so constructing the parts it will be obvious that when the cam 23 is swung into the position shown in Fig. 5, that portion 23^b of the cam which is farthest from the pivot will coöperate with the shoulder 26 of the sleeve 25, causing the latter and the wheel 3 with which it coöperates to move toward the wheel 5, thus moving the projection 17 into the path of the projection 18 on the wheel 5, rotary motion imparted to wheel 3 being transmitted through these coöperating projections to the wheel 5, the two wheels and their coöperating projections serving as clutch members. However, when the cam 23 is moved into the position shown in Fig. 6, the part 23^a of the cam nearest the pivot will rest against the shoulder 26 of sleeve 25, allowing the wheel 3 to separate from wheel 5 under the action of the compression spring 21 which is interposed between them, and this will cause the disengagement of the coöperating projections, so that the wheel 3 may continue to revolve 30 without transmitting motion to wheel 5, and the operation of the machine will be interrupted.

The fork reel 27 is rotatably mounted on the shaft 27, the latter being connected by 35 suitable mechanism such as that described in my application above-mentioned, whereby it may be rotated intermittently half a revolution at predetermined intervals timed according to the operations of the carriage 40 and the paring knife, so that the spindles 15 and 16 with their respective fruit forks are alternately brought into operative position relatively to the knife with their pinions 13 and 14 in mesh with the driving pinion 12 by means of which rotary motion is imparted to the spindles, causing the fruit to revolve while it is being pared, and as these spindles are revolved at high speed so that the surface of the fruit moves very rapidly 50 past the paring knife, and the knife blade in paring the ends of the fruit is arranged transversely to the axis of rotation, it has been found necessary to provide inexpensive and efficient means for taking up all end 55 thrust and longitudinal motion of the forks in order to insure uniformity in the paring of the fruit, and for this purpose I provide the reel with a pair of cross arms 28 and 29 by means of which the fork bearings are securely held. On the opposite ends of the arm 28 are formed the clamps 30 and 31 which are in alinement with the perforated bosses 33 on the arm 29 which receive the ends of sleeves 32. The clamps engage the 60 forward ends of the sleeves and comprise

the grooved portions 34 formed integral with the arm 28 and corresponding grooved plates or members 35 fitting the sleeves opposite the portions 34 and provided with a slot 36 in which is a clamping screw 37.

The pinions 13 and 14 bear against the rear side of the cross arm 29 as shoulders to limit the longitudinal motion of the spindles in one direction, and on the spindles are provided fixed collars 38 and 39 against 75 which are set the bearing members 35, and as the latter are adjustable axially of the spindles, by setting them up against their corresponding collars 38 and 39 on the respective spindles until the pinions bear 80 against the rear sides of the bosses 33, all looseness longitudinally of the spindles is taken up, and the end thrust from the forks is received on the adjustable bearing members.

In Figs. 7, 8 and 9 are shown an improved mounting for the paring knife, which consists of the vertical bearing 42 secured to and movable with the carriage 2 by means of the bracket 43 and screw 44, and in this bearing is journaled a shaft 45 having a radial arm 46 clamped thereon in adjusted position by means of the screw 47, the free end of this arm being forked and provided with preferably a pair of open trunnion bearings 48 which are arranged in the plane of rotation of the arm. The paring knife 49 is provided with a shank 50 on which is loosely mounted a sleeve 51 having trunnions or projections 52 thereon adapted to rest in the trunnion bearings 48 of the arm 46, a lateral arm 53 being fixed to the upper end of the paring knife shank behind the knife blade 49, and provided with a series of recesses to receive one end of a tension spring 54. The other end of this spring is attached to the free end of an arm 55 which constitutes the turntable, the latter being fixed to the lower end of the shaft 45 and provided with an extension 56 which is arranged to rest between 110 the projections 57 and 58 of the stationary frame. This arm is provided with a radial slot 59 in which the shank 50 loosely rests, and this slot has an opening 60 through 115 which the shank may pass in entering and leaving the slot, except when the projections 52 are resting in the bearings 48.

As the carriage 2 is movable relatively to the frame 1, the extension 56 of the turntable resting between the projections 57 and 120 58 on the stationary frame will operate as the tooth of a gear and cause the turntable to rotate and swing the paring knife through a semi-circular arc to perform the paring operation, the return motion of the carriage 125 causing the knife and its operating parts to return to normal position as shown in Fig. 1, the trunnion bearings for the knife permitting the latter to yield sufficiently to compensate for the irregularities in the surfaces 130

of the articles being pared, the upper end of the spring 54 being set at the proper notch in the arm 53 to set the knife under proper pressure. As the knife blades are quickly dulled and must be often replaced with sharp ones, it is important that the knife should be so mounted that they can be quickly and easily removed and replaced, and this has been provided for in the present 10 construction, for in order to remove the knife it is only necessary to lift the trunnions 52 out of their bearings 48 in the arm 46, and this will release the tension on spring 54 and by swinging the upper end of the shank to 15 the left in Fig. 7, it will pass through the opening 60 from the slot 59.

I claim as my invention:

1. In a paring machine, the combination 20 with a supporting frame, a fruit fork and a paring knife having a shank, of a turntable provided with a lower slotted arm for guiding the shank and an upper supporting arm, having open bearings therein, a sleeve loosely surrounding the shank having trunnions resting in said bearings, an arm secured to the shank above the sleeve and a

spring operating on the arm to yieldingly hold the paring knife in operative position on the turntable.

2. In a paring machine, the combination 30 with a frame, and a paring knife supported thereon, of a revoluble reel adapted to support a plurality of fruit forks provided with a forward and rear arm for each fork, a tubular bearing secured in each of the rear 35 arms and supported by the forward arms, spindles journaled in the bearings having forks thereon and each provided with a collar located at one side of its respective forward arm and a pinion abutting the rear 40 arm and limiting its outward movement and cap plates on each of the forward arms adjustable longitudinally on the bearings and coöperating with the collars to take up lengthwise lost motion of the spindles in 45 their bearings, and means for rotating the reel and driving the fork pinions.

WILLIAM H. BOUTELL.
